UNITED STATES PATENT OFFICE.

CHARLES E. PIERCE, OF EDMORE, NORTH DAKOTA.

WHIP-SOCKET.

No. 876,658.

Specification of Letters Patent.

Patented Jan. 14, 1908.

Application filed May 21, 1907. Serial No. 374,814.

To all whom it may concern:

Be it known that I, CHARLES E. PIERCE, citizen of the United States, residing at Edmore, in the county of Ramsey and State of North Dakota, have invented certain new and useful Improvements in Whip-Sockets, of which the following is a specification.

The present invention relates to certain new and useful improvements in whip sockets and resides principally in the provision of a novel structure whereby the whip is prevented from rattling when the vehicle is passing over a rough road, and whereby the whip can be locked against withdrawal when desirable.

The object of the invention is to provide a simple and inexpensive whip socket of this character which is strong and compact in structure and can be readily applied to any of the conventional types of vehicles.

For a full description of the invention and the merits thereof and also to acquire a knowledge of the details of construction and the means for effecting the result, reference is to be had to the following description and accompanying drawings, in which:

Figure 1 is a perspective view of a whip socket embodying the invention. Fig. 2 is a longitudinal sectional view through the same. Fig. 3 is a detail view of the shaft carrying the locking arm and the key for the locking mechanism. Fig. 4 is an enlarged perspective view of a portion of the main spring within the socket.

Corresponding and like parts are referred to in the following description and indicated in all the views of the drawings by the same reference characters.

Specifically describing the invention the numeral 1 designates the body portion of the whip socket which is in the nature of a tubular casing and is provided with the laterally extending brackets 2 and 3 carrying the clips 4 by means of which the whip socket can be mounted upon a dashboard in the usual manner. One of these brackets and in the present instance the upper bracket 2 has a hollow formation whereby a chamber 5 is produced, the said chamber being in communication with the interior of the whip socket and being designed to form a housing for the locking mechanism. A longitudinally disposed spring 6 is mounted within the tubular casing 1, the lower end of the spring being secured to the inner walls of the casing while the intermediate portion of the spring is bowed

outwardly so as to engage the whip handle when thrust within the socket. The free or upper end of the spring 6 extends over the mouth of the chamber 5 and is inclined inwardly so as to engage the end of the whip and coöperate with the same when the whip is being thrust into position to compress the spring in the required manner. The intermediate portion of the spring 6 is formed with a pair of laterally extending wings 7 which are bent forwardly and serve to embrace the whip handle.

Journalized within the lower portion of the chamber 5 is a transverse shaft 8 one end of which has a square or angular formation for engagement with the socket of a key 9 and extends within a recess 10 formed in the exterior of the bracket 2. Mounted upon the shaft 8 is a locking arm 11 which when swung rearwardly within the chamber 5 permits the whip socket to be used in the customary manner, while when swung forwardly it engages the spring 6 and forces the same into engagement with the whip handle so as to prevent withdrawal of the latter from the socket. A laterally disposed shoulder 12 is formed upon the rear face of the spring 6 adjacent the lower portion of the chamber 5 and is designed to engage the extremity of the locking arm 11 to limit the swinging movement thereof. It will be observed that this shoulder is so positioned that the locking arm 11 is inclined downwardly when moved into engagement therewith, whereby any tendency to withdraw the whip from the socket merely tends to force the spring 6 into a tighter engagement therewith.

In order to prevent the locking arm 11 from accidentally swinging into operative position due to the jolting of the vehicle a spring detent 13 is utilized which is in the nature of a strip having the upper end thereof secured to the interior of the tubular casing 1 immediately above the chamber 5, while the lower end extends downwardly and projects over the mouth of the chamber in such a manner as to engage the extremity of the locking arm 11 as the same is moved from one position to the opposite position. It will also be observed that the inwardly bent upper end of the main spring 6 bears against the spring detent 13 and slides upon the same, thereby preventing any binding of the parts when the whip is inserted in position. A swinging cover 14 is mounted upon the exterior of the bracket 2 and normally extends

over the recess 10 to prevent dust and rain from entering the same.

Having thus described the invention, what is claimed as new is:

- 5 1. In a whip socket, the combination of a tubular casing, a clamping spring mounted within the tubular casing, a swinging arm adapted to engage the clamping spring to move the same into an operative position, 10 and a spring detent to prevent accidental movement of the swinging arm.
2. In a whip socket, the combination of a tubular casing, a clamping spring mounted within the tubular casing and having one of 15 its ends secured thereto, a swinging arm adapted to engage the clamping spring to move the same into an operative position, and a spring detent to prevent accidental movement of the swinging arm, the free end

of the clamping spring having a sliding engagement with the spring detent.

3. In a whip socket, the combination of a tubular casing, a clamping spring mounted within the casing and provided with a shoulder, a swinging locking arm adapted to engage the clamping spring to force the same into an operative position, the said swinging arm engaging the before mentioned shoulder upon the clamping spring and being limited in its swinging movement in one direction 25 thereby, and a detent for holding the swinging arm against accidental movement.

In testimony whereof I affix my signature in presence of two witnesses.

CHARLES E. PIERCE. [L. S.]
